UNITED STATES PATENT OFFICE

ALBERT WILLIAM FREHSE, OF DETROIT, MICHIGAN, ASSIGNOR TO GENERAL MOTORS CORPORATION, OF DETROIT, MICHIGAN, A CORPORATION OF DELAWARE

INTAKE MANIFOLD

Application filed February 7, 1927. Serial No. 166,560.

This invention relates to internal combustion engines particularly to improvements in the heating of the carburetted mixture before it is drawn into the firing chamber, and in the application of an air straightener in the intake manifold.

The exhaust manifold preferably has a special shape adapted to suit the needs of my invention, and for this purpose I provide a plurality of depressed arched protuberances or bulges at the bottom thereof into which enter the leads from the intake manifold. In each of these bulges I locate an air or flow straightener (which per se forms no part of my invention) and the construction is such that the hot exhaust gas may circulate around the air straightener.

The air straightener may be positioned in the exhaust manifold in a number of ways. The heat may be applied directly to the straightener; or a metallic cylinder or collar may closely surround the straightener and the exhaust gases caused to come in contact with the cylinder; or I may allow a space between the collar and straightener and apply the heat to the collar thereby causing the heat to pass through the air space between the collar and the straightener.

The invention is disclosed in the accompanying drawing in which:

Figure 1 is a side view of so much of an internal combustion engine as is necessary to illustrate my invention.

Figure 2 is a plan view of the structure shown in Figure 1.

Figure 3 is a section on the lines 3—3 of Figures 1 and 4 with the air straightener shown in full lines.

Figure 4 is a section on the line 4—4 of Figures 2 and 3 showing the outer portion only of the air straightener.

Figures 5 and 8 are views similar to Figure 4 but showing modified forms of my invention.

Figure 6 is a section on lines 6—6 of Figure 5 with the air straightener shown in full lines.

Figure 7 is a section on lines 7—7 of Figure 8 with the air straightener shown in full lines. Figure 9 shows a sectional view of a fur-

ther modification with the air straightener shown in full lines.

Referring to Figure 1, 1 designates an internal combustion engine of any suitable type, 2 is the exhaust manifold, 3 the intake manifold, 4 the carburetor and 5 the exhaust tube.

By referring to Figures 2, 3 and 4 it will be seen that I have provided the intake manifold with a plurality of protuberances or bulges 17 at its lower portion and in these bulges are located the air straighteners 18. This straightener is shown as cylindrical but obviously may be of any suitable form. Surrounding each air straightener and in close contact therewith is a cylinder 20 having a flange 19 at one end resting on a seat 21 of the intake manifold and at its other end a flange 22 bent at right angles and seated in a recess 23 at the outer portion of the intake manifold. Surrounding the collar 20 there is a space 24 the purpose of which is to permit the hot exhaust gases to circulate around the collar.

An air straightener in practice is a copper tube having a honey comb like filler so as to form a plurality of small passages instead of a single large one. The carbureted fuel as it comes from the carburetor through the intake manifold is in a turbulent state and the purpose of the air straightener is to force the fuel mixture through the smaller passages of the air straightener and thereby decrease its turbulence and give it a smoother and more even flow to the firing chamber.

The intake manifold 3 is secured to the face of the exhaust manifold by means of a clamping ring 34 and the usual gasket 25 is applied between the clamping ring and the face of the exhaust manifold.

The species of Figures 5 and 6 differs from that shown in Figures 3 and 4 in that a space 26 is allowed between the collar 20' and the air straightener 18 and instead of the outwardly bent flange 23 of Figure 3; the collar 20' has an inwardly directed flange 23' which contacts with the outer end of the air straightener.

In the species shown in Figures 7 and 8 I show the air straightener positioned to receive the heat direct from the exhaust gases.

In this species no collar is used but a space 27 is provided between the air straightener 18 and the bulge 17'. This bulge 17' entirely surrounds the air straightener and the heat from the exhaust gases is communicated to the straightener across the wall of the bulge 17' and the space 27. At the outer end of the recessed portion there is provided an internal annular flange 28 which holds the outer end of the straightener 18.

In the species shown in Figures 3 and 6 the bulged portion 17 or 17' is provided with internal annular flanges 29 and 30 the purpose of which is to retain the collars 20 or 20' in their proper position. It will also be noted that the lower portion at the bulges is exposed to the cooling effect of the atmosphere in each instance.

From an examination of the different species it will be apparent that the carbureted mixture will be heated by the transmission of heat from the hot exhaust gases to the air straightener through the metal walls of the collars 20, 20' or bulge 17', and the passages 24, 26 or 27. The amount of heating will depend upon which species is used, the heating being greater, for example, with the species of Figure 3 than with the species of Figure 6.

From an inspection of Figure 3 it is obvious that the collar 20 may have its flange 19 bent at right angles and applied similarly to the flange 22. Likewise, the recess 23 may be omitted and the flanges at both ends applied to the inner and outer faces of the bulged portion 17, as shown at 19' and 22' in Figure 9, in which case the collar forms its own gasket.

In order that the hot exhaust gases may be deflected toward the air straightener I preferably provide blades or flanges 29 at the top of the exhaust manifold, forming an arched structure as is shown at 30.

I claim:

1. In combination with an internal combustion engine having intake and exhaust manifolds associated therewith, flow straighteners in said intake and surrounded by said exhaust manifold, a collar surrounding each straightener, each collar being spaced from both straightener and exhaust manifold.

2. In a heating device as applied to internal combustion engines having a carburetor and intake and exhaust manifolds associated therewith, and means for heating the carbureted fuel, said heating means comprising a plurality of flow straighteners forming continuations of the intake manifold and located within the exhaust manifold.

3. In combination with an internal combustion engine having intake and exhaust manifolds associated therewith, means for heating the engine fuel mixture comprising a plurality of flow straightener units within the intake manifold and surrounded by said ex-

haust manifold, and a collar surrounding each straightener unit.

4. In combination with an internal combustion engine having intake and exhaust manifolds associated therewith, means for heating the engine fuel mixture comprising a plurality of flow straightener units within said intake manifold and surrounded by said exhaust manifold, and a collar surrounding and embracing each straightener unit and secured to said exhaust manifold.

5. In combination with an internal combustion engine having intake and exhaust manifolds associated therewith, means for heating the engine fuel mixture comprising a plurality of flow straightener units within said intake manifold, and a collar surrounding each straightener unit, said exhaust manifold spaced from and surrounding said collars.

6. In combination with an internal combustion engine having intake and exhaust manifolds associated therewith, means for heating the engine fuel mixture comprising a plurality of flow straightener units surrounded by said exhaust manifold and within said intake manifold, a collar surrounding each straightener unit, and bulges in said exhaust manifold around said collars, said bulges spaced from said collars.

7. In combination with an internal combustion engine having intake and exhaust manifolds, each manifold having a plurality of arms, means for heating the engine fuel comprising a flow straightener in each arm of the intake manifold, each straightener surrounded by an arm of the exhaust manifold, and a collar between each straightener and the exhaust manifold.

8. In combination with an internal combustion engine having intake and exhaust manifolds, each manifold having a plurality of arms, means for heating the engine fuel comprising flow straighteners forming continuations of each arm of the intake manifold and each straightener surrounded by an arm of the exhaust manifold, and collars surrounding said straighteners.

9. In combination with an internal combustion engine having intake and exhaust manifolds, each manifold having a plurality of arms, means for heating the engine fuel comprising flow straighteners forming continuations of each arm of the intake manifold and each straightener surrounded by an arm of the exhaust manifold, and collars surrounding said straighteners and spaced from said exhaust manifold.

In testimony whereof I affix my signature.

ALBERT WILLIAM FREHSE.
